UNITED STATES PATENT OFFICE

2,297,118

GOLF PRACTICING DEVICE

Erich K. Wildegans, Providence, R. I., assignor to
 Paul-Rohland, Inc., a corporation of Rhode Island

Application August 6, 1940, Serial No. 351,612

3 Claims. (Cl. 273—35)

This invention relates to a golf-practicing device of the general character described in the application of Curt J. Rohland, Patent No. 2,213,570, entitled Golf apparatus; and this invention has for one of its objects to provide a construction which may be more easily and accurately inserted into the ground to attain a vertical position with reference to the surface of the ground in which it is inserted.

Another object of the invention is to provide a construction which, although hammered into the ground, will not change the pitch of the helical guide about which the tethered element to be driven is guided, and thus a more uniform golf-practicing device may be manufactured.

Another object of the invention is to provide an arrangement by which the driven element is always maintained captive and cannot escape from the post about which it spins.

Another object of the invention is to provide an apparatus which may be so disassembled that it may be compactly arranged in a carton for shipment.

With these and other objects in view, the invention consists of certain novel features of construction as will be more fully described and particularly pointed out in the appended claims.

In the accompanying drawing:

Fig. 1 is a perspective view of the golf apparatus in position for use, illustrating in dotted lines the position of the driven element as remaining captive on the post;

Fig. 2 is a side elevation with the base in section as shown in Fig. 1;

Fig. 3 is a perspective view of the base element 35 detached from the pin of the device;

Fig. 4 is an elevation, partly in section, of the pin with the guide and head member assembled thereon;

Fig. 5 is a sectional view on line 5—5 of Fig. 4;

Fig. 6 is an elevation of the helical guide alone;

Fig. 7 is a sectional view showing the manner of guiding the link or tether of the driven element about the pin.

Fig. 8 is a view similar to Fig. 4 of a modified construction.

In the use of golf-practicing devices as illustrated in the Curt J. Rohland patent above mentioned, it has been found that people attempt to drive the device into the ground with a hammer or some other implement with such force that the center post becomes bent and the pitch of the helix changes so that the accuracy of the measurement of a golf stroke is thrown off. Also, it is found that where two spurs are to be in-

serted into the ground the short one may cause the upright guide to be inclined somewhat to the horizontal. Further, by the utilizing of one piece of material for providing both the inserts into the ground and the fixing of this wire in the base, as illustrated in said patent, a rather large box is necessary for the packaging of a device of this character.

In order to improve upon these features, I have arranged a center pin which will directly take any thrusts of the hammer blow for driving it into the ground, and none of this force, due to resistance of the ground, will be transmitted to the helical member. In this manner a stronger 15 pin may be provided and a very accurate helical guide may be also provided. Further, I have arranged that the driven element may be maintained captive, and I have provided a separate base so that the base may come apart from the pin for more compact packing. I have also eliminated the separate spur which may cause the tilting of the guide pin from the vertical; and the following is a more detailed description of the present embodiment of this invention, illustrating the preferred means by which these advantageous results may be accomplished:

With reference to the drawing, 10 designates a base plate originally of generally rectangular construction and which has its corners 11 bent downwardly to provide spurs for insertion into the ground, forming the same octagonal in shape. An opening 12 is formed in the center of this plate through which a guide pin 13 may be inserted.

This guide pin, as illustrated more fully in Fig. 4, is pointed at its end 14 and has assembled upon it a helical guide 15, shown alone in Fig. 6. This guide consists of a coil of wire of a desired number of convolutions and of a certain predetermined pitch. At the ends of this coil, the wire is rolled into a small loop, designated 16 at one end, and 17 at the other end, which will tightly encircle and frictionally grip the pin 13 to hold the coil firmly in place upon the pin. A stop, as shown at 38 in Fig. 8, may be located below the coil 17. Suitable jigs and necessary pressure may be provided for positioning this coil upon the pin at a location such as shown in Fig. 4 so that the portion 18 of the pin extends above the frictional encircling and gripping coil 16. Upon this portion 18 a head member 19 is provided which has a neck 20 and a flange 21 and may be welded or otherwise secured in position.

When this pin is thus equipped with this heli-

cal coil and head member, it may be inserted through the hole 12 in the base 10 after the base is positioned in the ground to the extent that the coil 17 or stop 30 abuts the base and limits the insertion of the pin in the ground. 5 By this arrangement, the pin may be inserted vertically, and even if driven in by hammer blows which are struck upon the pin, these blows will be transmitted directly to the pin itself and will not be transmitted to the coil 16 which is 10 spaced slightly from the head end during initial insertion of the pin. The stop 30 which engages the base 10 will prevent pressure being exerted on the helical guide, even if the pin is driven beyond its intended limit of insertion. Thus, 15 there is no distortion of the pitch of the helix.

The driven element, designated 25, consists of an imitation golf ball, usually of soft sponge rubber. A link, 26, is secured to this driven element 25; and at the other end of this link 20 there is a loop 27, suitably secured, which encircles the pin or post 13 and which is guided in its path between the convolutions of the helix 15. Thus, as the driven element 25 is struck by the golf club, its tether 26 will allow it to swing about the post 13 until it passes out of the helical guide, and it will then swing about the neck portion 20 of the head until the energy imparted to this driven element is expended. 25

The foregoing description is directed solely towards the construction illustrated, but I desire it to be understood that I reserve the privilege of resorting to all the mechanical changes to which the device is susceptible. 30

I claim:

1. In a device for practicing the swing of a golf club, a pin to be inserted into the ground, a head on said pin comprising a collar embracing said pin with a flange extending outwardly at its upper end, a separate helical wire 40 guide about said pin and spaced therefrom, a ball having a tether provided with a loop at its end embracing the pin, said guide provided with a tight coiled portion frictionally and firmly

embracing said pin beneath said collar and arranged to deliver the looped end of the tether onto said collar for unrestricted rotation of said ball about the collar beneath said flange.

2. In a device for practicing the swing of a golf club, a pin to be inserted into the ground, a head on said pin comprising a collar embracing said pin with a flange extending outwardly at its upper end, a separate helical wire guide about said pin and spaced therefrom, a ball having a tether provided with a loop at its end embracing the pin, said guide provided with a tight coiled portion frictionally and firmly embracing said pin beneath said collar and arranged to deliver the looped end of the tether onto said collar for unrestricted rotation of said ball about the collar beneath said flange, the lower end of said helical wire being tightly coiled to frictionally and firmly embrace said pin and anchor said guide in position, and a plate through which said pin extends, said plate abutting the lower coil embracing said pin.

3. In a device for practicing the swing of a golf club, a pin to be inserted into the ground, a head on said pin comprising a collar embracing said pin with a flange extending outwardly at its upper end, a separate helical wire guide about said pin and spaced therefrom, a ball having a tether provided with a loop at its end embracing the pin, said guide provided with a tight coiled portion frictionally and firmly embracing said pin beneath said collar and arranged to deliver the looped end of the tether onto said collar for unrestricted rotation of the ball about the collar beneath said flange, the lower end of said helical wire being tightly coiled to frictionally and firmly embrace said pin and anchor said guide in position, and a plate through which said pin extends, and provided with downwardly bent spurs, said plate abutting the lower coil embracing said pin and acting as a stop to assist in driving the plate spurs into the ground by striking said head.

ERICH K. WILDEGANS.
